UNITED STATES PATENT OFFICE.

FRANKLIN L. BARBER AND EDWIN W. WEBB, OF CHICAGO, ILLINOIS, ASSIGNORS TO STANDARD CAR TRUCK COMPANY, OF CHICAGO, ILLINOIS, A CORPORATION OF NEW JERSEY.

CAR-TRUCK.

1,311,371.

Specification of Letters Patent. Patented July 29, 1919.

Application filed February 17, 1919. Serial No. 277,535.

To all whom it may concern:

Be it known that we, FRANKLIN L. BARBER and EDWIN W. WEBB, citizens of the United States, residing at Chicago, in the county of Cook and State of Illinois, have invented certain new and useful Improvements in Car-Trucks; and we do hereby declare the following to be a full, clear, and exact description of the invention, such as will enable others skilled in the art to which it pertains to make and use the same.

Our invention relates to improvements in car trucks, and particularly to six-wheeled equalized passenger car trucks. To the above end, the invention consists of the novel devices and combinations of devices hereinafter described and defined in the claims.

In the accompanying drawings, which illustrate the invention, like characters indicate like parts throughout the several views.

Referring to the drawings,

Figure 1 is a fragmentary plan view of the improved car truck, with some parts indicated by means of broken lines;

Fig. 2 is a view in longitudinal vertical section taken on the line 2—2 of Fig. 1, with some parts removed;

Fig. 3 is a side elevation of the improved truck;

Fig. 4 is a longitudinal vertical section taken through the side member of the truck frame shown in Fig. 3;

Fig. 5 is an end elevation of the improved truck, as shown in Fig. 1;

Fig. 6 is a view partly in elevation and partly in transverse vertical section taken approximately on the irregular line 6—6 of Fig. 1;

Fig. 7 is a view partly in elevation and partly in transverse vertical section taken approximately on the line 7—7 of Fig. 1; and

Fig. 8 is a view partly in elevation and partly in section taken on the line 8—8 of Fig. 1.

The truck frame, as shown, is made partly of cast steel and partly of rolled sections riveted together and which frame includes side members 9, end members 10 and two

pairs of laterally spaced transoms, the inner and outer members of which are indicated by the numerals 11 and 12, respectively. Each side member 9 of the truck frame is 55 rectangular in cross section, cast hollow with open ends, and provided in its outer side wall with openings 9'. The purpose of leaving the ends of the side members 9 open and providing the same with openings 9' is 60 to facilitate the casting of said side members and the assembling of certain of the parts of the truck. The end members 10 and transoms 11 and 12 are of channel formation with the flanges of each of said end members 65 and the adjacent transoms 11 turned horizontally toward each other and the flanges of the two transoms 12 are also turned horizontally toward each other.

Each end member 10 of the truck frame 70 is connected to the adjacent transom 11 by a pair of laterally spaced angle tie bars 13 and the two transoms 12 are connected by a pair of angle tie bars 14 alined with the tie bars 13. By reference to Fig. 5, it will be 75 noted that the end members 10 have a considerable drop, which extends substantially the full length thereof, and it will also be noted, by reference to Fig. 7, that the tops of the transoms 12 are dropped to afford 80 shoulders 15, and clearance for a casting, which connects the members of a double truck bolster, as will hereafter be noted. The ends of the tie bars 13 are connected, by 85 gussets 16, to the upper flanges of the end members 10, at the dropped portions thereof, and the upper flanges of the transoms 11. The ends of the tie bars 14 are seated against the shoulders 15 and their vertical and horizontal flanges are riveted to the 90 transoms 12.

End and intermediate pairs of pedestals 17 are located directly under each side member 9 of the truck frame and have mounted therebetween journal boxes 18. These pedestals 17 and journal boxes 18 are of the M. C. B. type, and the wheels and axles of the improved car truck are indicated by the numerals 19 and 20, respectively. Each pair of pedestals 17 comprises a pair of laterally spaced members, the upper ends of which 95 embrace the side members 9 of the truck 100.

frame and are bolted thereto. These laterally spaced members of each pair of pedestals 17 are rigidly connected by upper and lower cross bars 21, the former of which have directly supported thereon the side members 9 and are bolted thereto, and the latter of which cross bars 21 are connected by tie bars 21' that underlie the journal boxes 18.

- 10 The truck frame is supported from the journal boxes 18 by yokes 22, coiled springs 23 and equalizer bars 24. Each journal box 18 is transversely straddled by one of the yokes 22, which is supported on a fulcrum lug 25 cast with the top of the respective journal box, with freedom for limited rocking movement in a vertical plane. To hold the yokes 22 against endwise movement on the fulcrum lugs 25, shallow notches 26 are 15 formed therein. The lower edges of the yokes 22 are upwardly beveled or curved from their seats 26 to permit the required rocking movement of said yokes with respect to the journal boxes. The equalizer 20 bars 24 extend longitudinally within the hollow side members 9 of the truck frame, have arms of equal length and also have on their upper edges curved fulcrum surfaces 27, which directly engage depending fulcrum lugs 28 cast on the top walls of said 25 members. Lugs 29 on the equalizer bars 24, at the ends of the fulcrum surface 27, engage the lugs 28 to hold said bars against endwise movement.
- 30 The coiled springs 23 are compressed between spring seats 30 and spring caps 31 and said spring seats are supported on the ends of the yokes 22 and detachably secured thereto by dowels 32. The two spring caps 31, at the ends of the side members 9, bear directly against the bottoms of said side members and are detachably secured thereto by dowels 33. All of the other spring caps 31 have stems 34, which work through 35 apertures in the bottoms of the side members 9 and support on their upper ends the equalizer bars 24, as best shown in Fig. 4. It will be noted that the upper ends of the stems 34 are convex and fit in concave seats in 40 under edges of the equalizer bars 24, to permit the required rocking movement of the equalizer bars 24.

45 Pins 35, on the upper ends of the stems 34, loosely fit in bores formed in the equalizer bars 24 to hold said bars and stems in assembled relation. As there is not sufficient clearance between the side members 9 and journal boxes 18 for the yokes 22, longitudinal slots 36 are formed in the bottoms of 50 said side members to receive the intermediate portions of said yokes, and thereby permit the required vertical movement of said side members with respect to the journal boxes 18. These slots 36, together with the mem-

bers of the pedestals 17, between which the 65 arms of the yokes 22 project, hold said yokes properly positioned on the fulcrum lugs 25 and against lateral or angular turning movements. The dowels 32 and 33 and the stems 34 preferably have flat sides to prevent the 70 spring seats and spring caps from turning.

75 The members of a double truck bolster 37 are located, one member between each pair of transoms 11 and 12 and said members are rigidly connected by an H-shaped casting 38 bolted thereto at its ends and carries a center bearing plate 39. By reference to Figs. 1 and 7, it will be noted that the H-shaped casting 38 overlies the dropped portions of the transoms 12 and there is sufficient clearance therebetween to permit free 80 vertical movement of the truck bolster 37 with respect to the truck frame. The ends of the members of the truck bolster 37 project under and outward of the side members 9 of the truck frame and are further rigidly connected, in addition to the casting 85 38, by side bearing arch bars 40 bolted thereto.

90 Castings 41 are inserted between the transoms and members of the bolster 37 and riveted or otherwise rigidly secured to said transoms. These castings 41 act as guides or columns for the double truck bolster and they also serve as guides for combined 95 spring caps and spring bases, as will presently appear. The guides 41 are further secured to the transoms by forming hooks or shoulders 42 on their upper ends, which directly engage the upper faces of said transoms. U-shaped hangers 43 are suspended from the lower ends of the guides 41 and underlie the members of the truck bolster 37. The hangers 43 are detachably secured to the guides 41 by inserting through bores 100 in interlocking lugs formed on said hangers and guides headed pins 44, held in position by cotter pins. The members of the truck bolster 37 are supported from the hangers 43 by combined spring caps and spring seats 105 45, lateral motion rollers 46 and elliptical springs 47. The elliptical springs 47 rest on spring bases 48, which, in turn, are supported by the hangers 43.

110 The combined spring caps and roller bases 45 are carried by the elliptical springs 47 and support the rollers 46, which, in turn, support the truck bolster 37. In the under faces of the members of the truck bolster 37, are formed roller seats 49 for the rollers 115 46. The ends of the combined spring caps and roller bases 45 are notched to receive the guides 41 which hold said bases positioned for vertical movement under the action of the elliptical springs 47. By reference to Fig. 7, it will be noted that the ends of the pins 44 do not project outward 120 of the vertical edges of the guides 41 and,

therefore, do not interfere with the vertical movement of the combined spring cap and roller bases 45.

Stop lugs 50 are cast on the tops of the members of the truck bolster 37 and arranged to engage the inner faces of the side members 9 of the truck frame to limit the lateral movement of said bolster. Nut-equipped bolts 51 are passed through the side members 9 of the truck frame beneath the equalizer bars 24 and which bolts, together with the lugs 29, securely hold said equalizer bars against displacement. Brake hanger lugs 52 are cast integral with the end members 10 and transoms 11 and 12.

From the above description, it is evident that the load of the car is directly on the double truck bolster and it, in turn, is supported from the main frame by lateral motion bearing devices and elliptical springs. The weight of the truck frame is applied to the journal boxes through the equalizer bar 24, coiled springs 23 and yokes 22. By the construction and arrangement of parts just referred to, each wheel is allowed to move vertically and independently of the other thereof. In this design of the car truck, there is sufficient space or clearance between the elliptical springs and wheels for the use of brakes, of the clasp type, wherein the shoes thereof are arranged to engage the wheels at substantially diametrically opposite points.

The rollers 46 and their seats in the combined spring cap and roller bases 45 and the truck bolster 37 afford sufficient lateral motion for the truck frame, thus permitting the use of rigid hangers. All parts of the truck are rigid, except for their vertical movement and the lateral movement of the truck bolster. By detachably connecting the hangers 43 to the guides 41, makes it very convenient to assemble the movable parts of the truck, at the time of manufacture, or in making repairs.

What we claim is:—

1. In a car truck, the combination with a frame, of independent guides carried by the frame, displaceable hangers carried by said guides, and a bolster mounted between the guides and spring-supported from said hangers.

2. In a car truck, the combination with a frame, of independent guides carried by the frame, displaceable hangers carried by said guides, a bolster mounted between said guides, springs supporting the bolster from the hangers, and lateral motion devices interposed between the bolster and springs.

3. In a car truck, the combination with a frame, of independent guides carried by the frame, displaceable hangers carried by said guides, a bolster mounted between said guides, combined spring caps and roller

bases mounted between said guides and held thereby with freedom for vertical movement, springs interposed between said bases and hangers, and lateral motion devices interposed between the bolster and said bases.

4. In a car truck, the combination with a frame, of guides carried by the frame, hangers detachably secured to said guides, and a bolster mounted between the guides and spring-supported from said hangers.

5. In a car truck, the combination with a frame, of guides carried by the frame, hangers rigidly but detachably secured to said guides, and a bolster mounted between the guides and spring-supported from said hangers.

6. In a car truck, the combination with a frame, of guides carried by the frame, hangers carried by said guides, said guides and hangers having interlocking lugs with aligned bores through which are inserted pins that terminate within the vertical edges of said guides, and a bolster mounted between the guides and spring-supported from said hangers.

7. In a car truck, the combination with a frame having a pair of laterally spaced transoms, of a pair of guides on the inner faces of said transoms, displaceable hangers carried by said guides, and a bolster mounted between the guides and spring-supported from said hangers.

8. In a car truck, the combination with a frame having a pair of laterally spaced transoms, of guides on the inner faces of said transoms and having hook-like upper ends, engaging the tops of said transoms, hangers carried by said guides, and a bolster mounted between the guides and spring-supported from said hangers.

9. In a car truck, the combination with a frame having hollow side members and journal boxes, of yokes straddling the journal boxes, equalizer bars within said side members and fulcrumed on the tops thereof, spring bases on the arms of the yokes and equalizer bars, and springs mounted on said bases and having spring caps, certain of the spring caps having the frame as their base of resistance and the other spring caps having stems working through apertures in the bottoms of said side members and supporting the equalizer bars.

10. In a car truck, the combination with a frame having hollow side frames and journal boxes, of yokes straddling the journal boxes and fulcrumed thereon, equalizer bars within said side members and fulcrumed on overlying lugs, means locking said equalizer bars against endwise movement with respect to said lugs but separable therefrom by a downward movement, displaceable means underlying said equalizer bars for holding the same against downward movement with

respect to said lugs, and springs interposed between certain of the arms of the yokes and the frame and between the other arms of the yokes and the arms of the equalizer bars.

5 11. In a car truck, the combination with a frame, of guides carried by the frame, displaceable hangers carried by said guides, and a bolster mounted between said guides, and

springs and lateral motion devices supporting the bolster from the hangers. 10

In testimony whereof we affix our signatures in presence of a witness.

FRANKLIN L. BARBER.
EDWIN W. WEBB.
